Primary Examiner — T. Chase Nelson(74) *Attorney, Agent, or Firm* — Lee & Hayes, PLLC(57) **CLAIM**

The ornamental design for an optical media package, as shown and described.

DESCRIPTION

FIG. 1 is a right side perspective view of an optical media package;

FIG. 2 is a left side perspective view of the optical media package of FIG. 1;

FIG. 3 is a front elevation view of the optical media package of FIG. 1;

FIG. 4 is a back elevation view of the optical media package of FIG. 1;

FIG. 5 is a left side view of the optical media package of FIG. 1;

FIG. 6 is a right side view of the optical media package of FIG. 1;

FIG. 7 is a top side view of the optical media package of FIG. 1; and,

FIG. 8 is a bottom side view of the optical media package of FIG. 1.

The broken lines form no part of the claimed design. The claimed design extends to the broken line boundaries but does not include the boundaries or the areas within the boundaries.
